DISPENSING RACK

Peter Milton, Milwaukee, Wis., assignor, by mesne assignments, to Socony-Vacuum Oil Company, Incorporated, New York, N. Y., a corporation of New York

Application February 5, 1937, Serial No. 124,197

1 Claim. (Cl. 248—140)

This invention relates to improvements in dispensing racks.

It is customary for oil distributors and similar concerns to store oil and other liquids in drums holding approximately fifty-five gallons, and the contents of these large containers is then dispensed as needed into smaller five- or ten-gallon cans for delivery to retailers. The fifty-five gallon drums are provided with dispensing spouts and must be elevated to such a point and so supported that the spout will properly discharge into one of the smaller cans. Heretofore a number of dispensing racks have been provided which are capable of elevating and supporting a fifty-five gallon drum in a sufficiently high position to dispense its contents into five-gallon cans. These racks, however, are not constructed to permit discharge into ten-gallon cans. The only available devices suitable for use with cans of this latter size are either so difficult to operate that it requires more than one man to position a fifty-five gallon drum in the rack and elevate the same to dispensing position, or else the devices are so complicated and expensive as to render their use impractical for this limited purpose.

It is a general object of the present invention to provide a simple and relatively inexpensive device of the class described so constructed that a fifty-five gallon drum can be positioned therein and elevated by one man, the drum after being elevated attaining a sufficient height to permit discharge into either five- or ten-gallon containers.

A more specific object of the invention is to provide a dispensing rack having a drum supporting portion which is movable from an inclined drum loading position with one end adjacent the floor to an unusually high elevated dispensing position.

A further object of the invention is to provide in a device as above described, novel mechanism operable by one man for raising the drum supporting portion from loading position to the elevated dispensing position.

A more specific object of the invention is to provide a dispensing rack wherein said raising mechanism includes links forming a toggle joint and screw means for moving said links.

A further object of the invention is to provide a dispensing rack consisting of two substantially triangular frame portions, one of said triangular frame portions forming a base, and the other triangular frame portion being inverted in position and forming a rack and having its lowermost point pivotally connected to the uppermost

point of said first frame portion so that the free end of the rack is movable from an inclined loading position to an elevated dispensing position.

A further object of the invention is to provide an improved dispensing rack which is relatively small in size, strong and durable, and well adapted for the purposes described.

With the above and other objects in view, the invention consists of an improved dispensing rack and all its parts and combinations as set forth in the claim, and all equivalents thereof.

In the accompanying drawings illustrating one complete embodiment of the preferred form of the invention in which the same reference numerals designate the same parts in all the views:

Fig. 1 is a perspective view of the dispensing rack in loading position, a drum being shown adjacent thereto in upright position (full lines) and in loaded position (dot-and-dash lines);

Fig. 2 is a perspective view of the rack in dispensing position, the dot-and-dash lines showing a supported drum and a ten-gallon container into which the drum is adapted to discharge;

Fig. 3 is a plan view of the screw mechanism, parts being broken away and shown in section; and

Fig. 4 is an enlarged detail view of the toggle joint and associated screw mechanism, dot-and-dash lines indicating the positions of the parts when the rack is in loading position and the full lines indicating the positions of the parts when the rack is in dispensing position.

Referring more particularly to the drawings, the device consists in general of two substantially triangular frame parts 5 and 6, the part 5 forming a base and the part 6 forming a movable supporting rack.

The frame portion 5 has its bottom formed of a plurality of angle irons 7, 8, 9 and 10, or other suitable structural material, secured together in a rectangular formation. Extending upwardly from each end of the angle member 10 are upright portions 11 and the upper ends of said members 11 are in turn connected by a member 12 of angle iron or other suitable material. The upper ends of the uprights 11 are connected by other members 13 with the ends of the bottom member 8. The result is a substantially triangular frame wherein the uprights 11 correspond to the short legs of the triangle, and wherein the bottom forming members 7 and 9 correspond to the long leg of the triangle; the members 13 corresponding to the hypotenuse.

The upper frame portion 6 is similarly con-

structed of parts 7' to 13' inclusive. The part 10' of the upper frame portion 6 is however not positioned directly at the corner of the frame. In addition, the members 7' and 9' are connected by concave bands 14 for supporting the drum.

The lower ends of the members 11' have lugs 15 depending therefrom and the upper ends of the members 11 have lugs 16 projecting upwardly. A channel 17 opening toward the interior of the frame and having closed ends is positioned between the lugs 15. Pivot bolts 18 on each side extending through the lugs 15 and 16 and the ends of the channel 17 pivotally connect the upper frame portion 6 to the lower frame portion 5 and at the same time pivotally connect the channel 17 between the lugs.

While it is contemplated that various means may be employed for pivotally moving the upper frame portion 6, nevertheless the particular mechanism shown is highly efficient. This mechanism includes links 19 pivotally connected at their upper ends as at 20 to the frame 6 and links 21 pivotally connected at their lower ends as at 22 to the frame 5. All of said links converge toward one another to an intermediate point in the interior of the frame work where they are pivotally connected together and to the end of a clevis 23 by a pivot bolt 24 (see Fig. 3). The outer end of the clevis has a nut 25 secured therein and a screw 26 projecting from the clevis is cooperable with said nut. The outer end of the screw 26 projects rotatably through the channel 17, as shown in Fig. 4, and through a group of washers 27 adjacent the closed side of the channel, the portion of the screw which passes through the channel and the washers being unthreaded. The extreme outer end portion of the screw which projects from the washer is flattened as at 28 to cooperate with a squared aperture in a crank handle 29, and said flattened outer end has its side portions threaded as at 30 for the reception of a lock nut 31.

Any suitable means may be employed in connection with the base portion 5 for facilitating movement of the rack over the floor. For example, a single roller 35 may be used at one end of the device as shown or rollers may be employed at both ends. It is also possible to utilize casters at the corners of the base.

In the use of the device, a drum 32, usually of the fifty-five gallon capacity, is placed in upright position adjacent the end of the dispensing rack opposite the crank handle as shown in Fig. 1. One man can then readily tilt the drum to the dot-and-dash line position of Fig. 1 and lift its lower end upwardly within the end portion 8' of the rack so that the curvature of the drum fits

against the ends 14. Then by turning the crank 29, the clevis 23 is pulled toward the crank handle by the screw action to move the links 19 and 21 from the dot-and-dash line position of Fig. 4 to the full line position therein. During such movement, the screw and clevis must also pivot and this is taken care of by having the outer end of the screw extending through the pivotally mounted channel 17. During such movement of the links, by the screw action, the frame portion 6 and drum carried thereby are moved from the position of Fig. 1 to the position of Fig. 2.

It is to be noted that the particular frame arrangement provides for elevation in a simple manner to an unusual height, considering the simplicity of the structure. This is brought about because of the fact that the pivot 18 between the frame portions 5 and 6 is located a substantial distance above the floor and because said pivot is also located a substantial distance below the drum supporting portion of the rack. The result of the structure is that the drum is elevated a distance equal to twice the height of the upright members 11 of the base, or at a height amply sufficient to permit placing of a ten-gallon container 33 below the spout 34 of the drum. The screw and toggle arrangement is also employed for lowering the drum after its contents have been discharged, and the lowering is accomplished by merely rotating the crank in a reverse direction.

Racks now on the market, having the simplicity of construction of the present invention, are only capable of elevating a drum to about half the height possible with the present invention, and therefore drums supported by these prior racks are not at a sufficient elevation to permit the insertion of a ten-gallon container there-beneath.

Although only one form of the invention has been shown and described, it is obvious that various modifications may be made without departing from the spirit of the invention, and all of such changes are contemplated as may come within the scope of the claim.

What I claim is:

A dispensing rack comprising a base, uprights rising from one end of said base on opposite sides thereof, a frame member including inverted L shaped sides which are pivotally connected at one end to said uprights whereby said frame is adapted to swing in a vertical plane, the ends of the L shaped sides of the frame remote from the pivot being adapted to swing from a position near the base to a position substantially above the point of pivotal connection, and means including a screw for raising and lowering said frame.

PETER MILTON.
